UNITED STATES PATENT OFFICE

ERNEST C. RUMOHR, OF SEATTLE, WASHINGTON

TREE SAWING DEVICE

Application filed October 21, 1931. Serial No. 570,203.

This invention relates to improvements in a tree cutting apparatus, and has for its object to provide an apparatus of this character, by means of which, a power operated saw may be conveniently applied, and a standing tree quickly cut in two.

Other features and objects will appear as the invention is more fully hereinafter described and explained in the following specification, shown in the accompanying drawings, and finally pointed out in the appended claims.

In the drawings:

- Fig. 1 is a plan view of the apparatus.
 15 Fig. 2 is a side elevation of same.
 Fig. 3 is a detail sectional view taken on the line 3—3 of Fig. 1.
 Fig. 4 is a cross sectional view of the eccentric.
 20 Fig. 5 is a detail sectional view taken on the line 5—5 of Fig. 1.
 Fig. 6 is a detail view, showing mechanism for feeding the saw.

Fig. 7 is a side elevation showing a tree partly sawed, and a screw means for holding the sawed parts spaced away from each other.

Referring now more particularly to the drawings, reference numeral 1 indicates a base, secured to which is a bearing 2, through which passes a shaft 3, upon one end of which is a gear 4. The opposite end of the shaft passes through a bearing 5, extending upwardly from an arm 5—a, which is bent upwardly from the base and has a flange 5B. Extending upwardly from the base 1 are bearing blocks 6 and 7, secured in place by means of bolts 8. 9 is a motor secured to the base by means of bolts 10. To the shaft of the motor is secured a gear 11, which meshes with the gear 4. 12 is an eccentric member mounted on the shaft 3. 13 is an extension from a strap associated with the eccentric and which will be presently described. Pivoted to the extension 13 is one end of a pitman rod 14. The opposite end of the pitman rod 14 slidably passes through a bearing 15, and its right hand end, Fig. 1, is secured at 15—a to one end of a saw 15—b. A strap 16 is fitted on the periphery of the eccentric 12, the strap being concave on its

inner surface to snugly engage the convex periphery of the eccentric. Obviously when the shaft 3 is rotated, the eccentric 12 will impart reciprocatory motion to the pitman rod 14, and the saw 15—b. The eccentric 12 is keyed to the shaft 3 at 17, so that the eccentric rotates with the shaft 3 and also is permitted to slide back and forth on the shaft. 18 is a boss rigid with the eccentric 12, and through which the shaft 3 freely passes. The boss is enlarged as at 19 and is provided on its periphery with an annular groove 20. 21 is an arm, one of whose ends is secured by bolts 22 to a boss 22—a extending from the bearing 15. The opposite end terminates in yoke members 23, (Fig. 3), which extend into the annular groove 20 of the boss 18. Through the bearing 15 passes a screw threaded shaft 24, mounted in bearings in the blocks 6 and 7. 25 is a shaft passing through blocks 6 and 7 and the bearing 15 so that the bearing 15 is permitted to slide upon the shaft 25. 26 is a shaft identical with the shaft 25 and slidably passes through the bearing 15 and has bearings in the blocks 6 and 7. 27 is a projection from the bearing block 6 which is bored through to receive one end of a shaft 28, the opposite end of said shaft fitting in a similar bearing 29 extending from a block 30, identical with the block 6.

The description just made of the left hand end of the apparatus describes the right hand end, (Fig. 2), with the exception that the description of the left hand end, included the motor, eccentric, et cetera. To each end of the shaft 28 is a gear 31. The gear at the left hand end of the shaft 28 meshes with a similar gear 32 upon the shaft 24. The gear 31 at the right hand end of shaft 28 meshes with a similar gear 33 upon the shaft 34 identical with shaft 24. Upon one end of the shaft 34 is a crank 35, so that by turning the crank, both shafts 24 and 34 are caused to rotate, thus feeding the saw 15—b against the work, which as shown in the drawings, is a tree, indicated at 36. 37 is a link, one end of which is pivotally connected to an arm 38 mounted on the shaft 24 and provided with a pawl 39, which coacts with a toothed wheel 40 rigidly secured to the screw shaft 24.

The opposite end of the link 37 is pivotally connected at 41 to a disc 42 secured to the shaft 3. By this arrangement, when the shaft 3 is rotated, the link 37 is reciprocated, causing the arm 38 to oscillate, which, through the pawl 39, imparts a rotative movement to the screw shaft 24. The result of this is that the bearing 15 is advanced, carrying the saw 15—b with it against the work, and through the gears 31, shaft 28, and gears 33, the bearing 44 is set or advanced forward in the same manner. The eccentric 12 and arm 21 also, of course, move with the bearings 15 and 44.

15 45 indicates jaw blocks which are slidably mounted upon rods 46 which pass through bearings 47. The left hand pair of the bearings 47, (Fig. 1), are secured to the base 1 by bolts 48. The right hand pair of bearings 20 47 are secured to a plate 49 by means of bolts 50. 51 indicates bolts which pass through bosses 52 extending from the bearing blocks 45, and are provided with nuts 53, so that by turning the nuts, the jaw blocks 45 are drawn 25 towards each other in a transverse direction so that the boss of the jaw blocks will sink into the tree to be sawed.

In operation, one of the rods 46 is pulled 30 through its bearing, and the apparatus is moved up to a tree, with the saw 15—b in contact with one side of the tree. The rod 46, which was removed, is now replaced so that the apparatus embraces the tree, as 35 shown in Fig. 1. The nuts 53 are now adjusted to cause the jaws 45 to sink into the surface of the tree and firmly grip the same, and thereby hold the apparatus in operative position. The motor is then started, which, 40 through the shaft 3, eccentric 12, strap 16, pitman rod 14, causes the saw 15—b to reciprocate and saw into the tree. As the sawing operation progresses, the saw is fed 45 into the tree through the feeding mechanism already described, including the block 38, pawl 39, disc 42, and link 37.

When the apparatus is placed in its position, as shown in Fig. 1, ready to begin the sawing, the crank 35 may be turned so as to advance the saw up to the work.

50 When the tree is sawed sufficiently through to tend to clamp the saw, a threaded wedge 36—a may be introduced behind the saw so as to wedge up the left hand side of the partially sawed tree, as shown in Fig. 7.

55 While I have shown and described a particular form of embodiment of my invention, I am aware that many minor changes will readily suggest themselves to those skilled in the art without departing from the spirit and scope of my invention. I therefore desire to avoid being limited to the particular form of embodiment which I have hereinabove shown and described.

What I claim is:

65 1. A tree sawing apparatus comprising a

pair of jaw blocks for engaging a tree, parallel rods carried by said jaw blocks, pairs of bearings on said parallel rods and carried on opposite sides of the jaw blocks, a pair of parallel shafts carried by said bearings by 70 means of end blocks connecting the shafts of each pair together supported from said bearing, a threaded shaft associated with each pair of parallel shafts, a block threadedly mounted on each of said threaded shafts, 75 a saw reciprocally carried by said threadedly mounted blocks, a motor for reciprocating said saw, and a ratchet mechanism connected with the motor for turning the threaded shafts and advancing the saw during the 80 sawing operation.

2. A tree sawing device as claimed in claim 1, with manually operated means for initially moving the saw to tree-engaging position.

In testimony whereof I affix my signature. 85

ERNEST C. RUMOHR.
